UNITED STATES PATENT OFFICE.

WILLARD IRVING TWOMBLY, OF NEW YORK, N. Y.

DESIGN FOR A COVERED VEHICLE-BODY.

50,637.

Specification for Design.

Patented Apr. 17, 1917.

Application filed October 26, 1914. Serial No. 868,772. Term of patent 3½ years.

To all whom it may concern:

Be it known that I, WILLARD IRVING TWOMBLY, a citizen of the United States, residing in the borough of Manhattan, in the city, county, and State of New York, have invented a new, original, and ornamental Design for Covered Vehicle-Bodies, of which the following is a specification.

This invention relates to the design of a covered vehicle body, and it is the object of the invention to provide a design for a covered vehicle body which is useful, has grace-

ful outlines, and an appearance of compactness and lightness.

The figure of the drawing is a perspective view of a covered vehicle body showing my new design.

I claim:

The ornamental design for a covered vehicle body, as shown.

W. IRVING TWOMBLY.
